(57) **CLAIM**

The ornamental design for confection, as shown and described.

DESCRIPTION

FIG. 1 is a front, left right perspective view of confection showing our new design;

FIG. 2 is a front view of the design shown in FIG. 1;

FIG. 3 is a back view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is a front, left perspective view of another embodiment of the confection showing our new design; and,

FIG. 9 is a front view of the design shown in FIG. 8.

The broken lines shown in the drawings illustrate portions of the design and form no part of the claimed design.
